US00D594767S

(12) **United States Design Patent**
Brockington et al.

(10) **Patent No.:** US D594,767 S
(45) **Date of Patent:** ** Jun. 23, 2009

(54) **PRECISION LEVEL**

(75) Inventors: **William T. Brockington**, Kernersville, NC (US); **Anthony D. Moore**, Summerfield, NC (US)

(73) Assignee: **Camco Manufacturing Inc.**, Greensboro, NC (US)

(**) Term: **14 Years**

(21) Appl. No.: **29/307,288**

(22) Filed: **Apr. 10, 2008**

(51) **LOC (9) Cl.** 10-04

(52) **U.S. Cl.** D10/69

(58) **Field of Classification Search** D10/69; 33/365, 366.11–366.27, 367–391

See application file for complete search history.

Primary Examiner—Antoine D Davis

(57) **CLAIM**

The ornamental design for a precision level, as shown and described.

DESCRIPTION

FIG. 1 is a top plan view of a precision level according to the invention;

FIG. 2 is a front elevational view of the invention;

FIG. 3 is a bottom plan view of the invention;

FIG. 4 is a rear elevational view of the invention;

FIG. 5 is a right elevational view of the invention, the left elevational view being a mirror image;

FIG. 6 is a top, front right perspective view of the invention;

FIG. 7 is a bottom, front left perspective view of the invention; and,

FIG. 8 is a rear, right top perspective view of the invention.
